LANTERN

Ernest H. Adams, Sr., Huntington Park, Calif.

Application September 28, 1937, Serial No. 166,105

4 Claims. (Cl. 240—27)

My invention pertains particularly to a lantern designed especially for service as a warning or danger light for various construction work on roads, highways, side-walks or the like or where any such red light lanterns are used and left over night, usually without any guard or watchman on duty. Practically all construction companies using lanterns for this purpose find that the lanterns have the coal oil poured out and stolen by petty thieves and hence the lantern becomes extinguished during the periods of darkness, subjecting such companies to damage claims for accidents caused by the lanterns becoming extinguished. My invention therefore comprehends a construction of the oil reservoir of the lantern whereby oil cannot be readily poured out of the lantern unless the wick assembly is removed. There is also a considerable breakage of the globes due to these being improperly protected and moreover the globes are somewhat expensive to replace, therefore my invention includes removable glass panels, these being each comparatively inexpensive and the maintenance man may readily carry a considerable number of these to replace individual broken panels.

Another feature of my invention which is operative to deter theft of the lanterns is that I provide a partially open suspension eye for the lantern whereby such lantern may only be carried on the finger or a rod and cannot be suspended on a small device such as a nail, this taking the place of the ordinary bail and as it is inconvenient to suspend the lantern, I find there is less petty thieving of these types of lanterns. Moreover the present lanterns do not provide any conspicuous space for the name of the owner of the lantern. My construction therefore provides a series of upright stiles which afford supports for the small window panes and also provide an outside surface on which the name of the owner of the lantern may be impressed, the material of construction being sufficiently soft for such purpose. Therefore this construction by having the name of the owner in a distinct and conspicuous position on the lantern deters the petty thieving. Other features of my invention include an improved air draft for the burner to supply air to the wick, the manner of hinging the chimney part of the lantern to the oil reservoir and also of hinging or attaching the cap to the chimney or stack part of the lantern.

My invention is illustrated in connection with the accompanying drawing, in which:

Fig. 1 is a side elevation of the lantern taken

substantially in the direction of the arrow 1 of Fig. 4.

Fig. 2 is a horizontal section on the line 2—2 of Fig. 1 in the direction of the arrows.

Fig. 3 is a horizontal section on the line 3—3 of Fig. 1 in the direction of the arrows, omitting the base or reservoir portion of the lantern.

Fig. 4 is a plan showing the reservoir and burner portion of the lantern taken in the direction of the arrow 4 omitting the frame of a chimney.

Fig. 5 is a vertical transverse section on the line 5—5 of Fig. 4 in the direction of the arrows showing the air supply for the wick burner, the burner being removed.

Fig. 6 is a vertical section on the line 6—6 of Fig. 4 in the direction of the arrows, the burner being again removed.

Fig. 7 is an elevation partly broken away of part of the burner to show the air circulation for the wick.

The oil filling construction which also prevents draining oil from the reservoir is substantially as follows, designated by the assembly numeral 11. The oil reservoir 12 is of a conventional type having a bottom 13, a circular side wall 14, a top 15 with a cone shaped upwardly extending section 16 and a neck 17 through which the wick extends. A sleeve 18 extends upwardly from the top and is secured thereto.

A filler tube 20 has an upper end 21 which extends through an opening in the top and is secured thereto to prevent leakage, this being threaded as indicated at 22 for attachment of a closure plug. The tube has a vertical downwardly extending portion 23 below the top and from this there is a laterally extending tubular arm 24, terminating at the open end 25. The filler end is on one side of the reservoir and the open end 25 located in a remote position leaving a clearance through the neck 17 for the wick. The open end is located above the bottom as indicated by the measurement numeral 26. It is also spaced from the top as indicated by the measurement line 27 and from the wall as indicated by the measurement line 28.

By this construction when the burner and wick assembly is in place, the fuel oil cannot be poured out of the end 21 after removal of the plug by tilting or inclining the reservoir, for when this is tilted up to position the end 21 in a low position, the oil level, unless of course the lantern is absolutely full, will be below the open end 25, hence the oil cannot flow through this end and the tubular arm 24. Of course if the lantern is

completely turned upside down, the oil would leak out through the wick opening but the petty thieving of oil is usually by persons endeavoring to pour the oil out of the filler tube or opening 5 after removing the plug and this is prevented by my construction.

The air supply assembly designated by the numeral 35 for the burner assembly has two air inlet tubes 36, each of which has an upright portion 37 and a horizontal portion 38, the horizontal portion extending through the openings 39 in the sleeve 18 and positioned contiguous to the cone portion 16 of the top. It will be noted that the horizontal sections 38 of the two opposite air tubes are not directly opposite but are slightly offset as shown in Fig. 4. Therefore these discharge air into the sleeve 18 and develop a circular motion of the air in this sleeve.

The wick mounting is somewhat conventional and designated by the numeral 40. This has a top 41 with a slot 42 through which the wick 43 extends, the wick passing downwardly through a flattened wick tube 44. The lower structure 45 of the burner is shaped to fit in the neck 17, 25 this having a snug fit. A skirt 46 fits on the outside of the sleeve and a shaft 47 for raising and lowering the wick has an operating head 48. The shaft extends through slots leading from the upper edge of the sleeve 18 and also leading upwardly from the lower edge of the skirt 46, this being substantially conventional. An air inlet control ring 49 is formed integral with the lower portion 45 of the burner structure and has a series of air apertures 50. These communicate 35 between the space 51 defined by the skirt 46 and the sleeve 18 and conduct the air which flows in through the air inlet tubes 35 upwardly to the wick and as this air has a swirl, such swirl is continued upwardly in the upper portion 41 of the burner cap and flows around the wick, the slot 42 conforming to the usual practice and being considerably larger than the cross section of the wick. This develops improved burning qualities of the oil from the wick.

The chimney construction of the lantern designated by the assembly numeral 55 includes a bottom ring 56 which is hinged at 57 to one side of the reservoir 11 and at the opposite side may be caught by a latch 58, this being of a conventional type. A plurality of spaced vertical legs 59 extend upwardly from the ring 56 and are secured to a circular diaphragm 60 which has a central opening 61 for the burner and a perforated annular section 62 to provide an up-draft of air. A plurality of channel type of stiles 63 extends upwardly from the diaphragm 60, terminating at a band 64 from which there are short upright sections 65 leading to a top ring 66. The lid or cover 67 is connected by a hinge 68 to the top ring and is secured to this ring on the opposite side by a spring latch or the equivalent. The suspension hook 70 has two side plates 71 forming a substantially circular eye 72 with an opening 73 at the top. This opening prevents hanging the lantern on a nail, wire or the like and for carrying the lantern it is either necessary to insert the fingers through the eye 72 or to string a series of lanterns on a bar or pipe. On account of the lantern lacking a facility for hanging the same, the theft of the lantern is discouraged.

70 A series of glass panels or windows 75 are formed of elongated strips of glass fitted in

marginal guide grooves 76 on the inside of the vertical stiles 63. These may be inserted from the top inside of the top ring 66 and the band 64. They rest at the bottom on the diaphragm 60 outside of the perforated section 62. This construction therefore allows ready inserting and removing of the glasses and facilitates change from a danger signal such as red to clear transparent glass to afford visibility. Another characteristic of my invention is making the stiles 63 on the outside with a flat surface indicated at 77 and of somewhat soft material so that by means of a letter die, the name of the owner of the lamp may be impressed on one or more stiles. By having this impressed in the metal and on a number of stiles, it does not matter whether an attempt is made to paint over the name as it will usually show on one or more of the stiles. Thus by having the name of the owner clearly and conspicuously presented on the lantern, a theft 20 of the lantern is discouraged.

Various changes may be made in the details of the construction without departing from the spirit or scope of the invention as defined by the appended claims.

I claim:

1. In a lantern having an oil reservoir with a wick and burner assembly, a chimney construction including a bottom ring, a plurality of spaced legs extending upwardly therefrom and connected to a diaphragm construction encircling part of the burner and wick, a plurality of parallel stiles extending upwardly from the diaphragm, each stile having a pair of channel guides, a top ring at the upper end of the stiles 35 having an opening positioned outwardly from the said channel guides, plane glass panels fitted in the guides between contiguous stiles, the said panels being insertable and removable adjacent the upper ring.

2. In a lantern as claimed in claim 1, a cover hinged to the upper ring and having an eye with an opening at the top.

3. In a lantern having an oil reservoir with a burner assembly, a chimney extending thereabove, a cover secured to the chimney, a structure forming an eye on the upper end of the cover, said eye having an opening at the top, the space formed by the said opening being less than the space across the eye.

4. In a lantern having an oil reservoir with an annular flat top surface and a burner and wick assembly positioned centrally of such annular surface combined with a chimney construction including a bottom ring hinged to one side of the reservoir and constructed and adapted to rest on the flat annular surface, a plurality of spaced legs extending upwardly from the bottom ring, a transverse annular diaphragm connected to the legs and encircling the burner and wick assembly, a plurality of parallel stiles extending upwardly from the diaphragm and connected therewith, each stile having a pair of channel guides with an outer exposed flat surface, a top ring at the upper end of the stiles having an opening positioned outwardly from the channel guides, plane glass panels fitted in the guides between contiguous stiles, the said panels being insertable and removable adjacent the opening of the upper ring and resting at the bottom on the annular diaphragm.

ERNEST H. ADAMS, SR.
